UNITED STATES PATENT OFFICE

THOMAS RAY AND JOSHUA R. RAY, OF MANISTEE, MICHIGAN

SEPARATING APPARATUS

Application filed March 1, 1928. Serial No. 258,419.

The invention pertains to the general class of separating apparatus and particularly to centrifugal separators. An object of applicants' invention is the production of a separator wherein a large part of the sediment extracted from the filtrate is removed continuously while the separator is in operation. A further object of applicants' invention is the production of a separator that may be readily cleaned. A further object of applicants' invention is the production of a separator that may be operated over a relatively long period of time without the necessity of shutting down for the purpose of removing the sediment. A further object of applicants' invention is the production of a separator durable in construction, economical to operate, of low cost, relatively small number of parts and positive in operation.

Many other objects and advantages of the construction herein shown and described will be obvious to those skilled in the art from the disclosure herein given.

To this end our invention consists in the novel construction, arrangement and combination of parts herein shown and described, and more particularly pointed out in the claims.

In the drawings, wherein like reference characters indicate like or corresponding parts:

Fig. 1 is a front elevation of the separator;

Fig. 2 is an end view of the feeding end thereof;

Fig. 3 is a sectional elevation on line 3—3 of Fig. 2;

Fig. 4 is a view taken on line 4—4 of Fig. 3;

Fig. 5 is a view taken on line 5—5 of Fig. 3;

Fig. 6 is a view taken on line 6—6 of Fig. 3;

Fig. 7 is a view taken on line 7—7 of Fig. 3; and

Fig. 8 is a section on line 8—8 of Fig. 1.

Referring now to the drawings, 1 shows a centrifugal separator mounted upon a shaft 2 supported in bearings 3 at each end of the separator. To one end of the shaft is attached a pulley 4, by means of which the separator 1 is revolved.

Referring now to Fig. 3, the body of the separator is composed of two central sections

5 and 6, a feeding end section 7 and a discharge end section 8. Sections 5, 6, 7 and 8 are secured together and supported on shaft 2 by means of spiders 9. The spiders 9 have disc portions 10 adjacent the shaft 2. The 55 discs 10 at their outer ends terminate in spaced legs 11 (see Fig. 7). The outer ends of the legs 11 are joined by an integral ring 12. Sections 5, 6, 7 and 8 are provided with flanges 13 and secured by suitable means to 60 the spiders 9 as clearly shown in Fig. 3. The flanges 13 on sections 5, 6, 7 and 8 are attached to the spiders 9 just within the annular ring 12. A heavy metal band 14 is shrunk about each of the annular rings 12, thus holding the structure rigidly together.

Extending lengthwise of the separator between and attached to the spiders 9 are vanes 15. The end section 7 is provided with manholes 16 and 17 which are closed by manhole 70 covers 18 and 19, respectively. End section 8 is provided with manholes 20 and 21 which are closed by manhole covers 22 and 23, respectively. Each of the manholes 16, 17, 20 and 21 is bisected by the plane passing 75 through the vanes 15. The purpose of this particular arrangement is to allow entry to either side of the separator through any one of the manholes.

End section 7 is formed about its central 80 portion with an inwardly converging frusto-conical portion 24. The inner circumferential edge 25 of the frusto-conical portion 24 is spaced from the shaft 2 and from the collar 26 of the adjacent spider 9 for the purpose of providing a space through which the filtrate may enter the separator proper.

Mounted upon shaft 2 is a combined feeding, sediment extracting member 27. The member 27 is not fixed to shaft 2 but remains 90 stationary when the shaft 2 is in motion. The member 27 has a portion 28 of uniform diameter in which is an annular passage 29 open at its inner end 30. Adjoining the portion of uniform diameter 28 is a frusto-conical portion 31 which extends outwardly toward the larger end of frusto-conical portion 24 of end section 7 and forming therewith sediment extracting chamber 32. Attached to shaft 2 within chamber 32 is an im- 100

steller 33 with a plurality of vanes 34, the purpose of which is to impart a revolving motion to the liquid as it enters into chamber 32 through open end 30 of passage 29.

5 Formed in the walls of the member 27 is a passage 35. Passage 35 begins at the outer end 36 of the frusto-conical portion 31 where the passage opens into chamber 32. The passage has preferably a cup-shaped extension 37 which extends outward into the chamber 32 and faces toward the impeller 33. Passage 35 is preferably curved adjacent its ends 36 as shown at 38. The passage then extends toward the outside through the frusto-conical portion 31 and preferably straight through the portion of uniform diameter 28. Passages 35 and 29, however, are kept distinct from one another. The flow and the fluidity thereof may be controlled by a valve 20 39 or other suitable means. Passage 35 has an outlet 39. Passage 29 has an inlet 40 through which the liquid to be separated enters the filter.

In order to prevent leakage from the chamber 32, a cover 41 is provided on the outside 25 of the frusto-conical portion 31. Cover 41 is secured to end section 7 and is located centrally thereof by means of an annular ring 42 on end section 7. The liquid thus cannot 30 escape around the edges of the frusto-conical portion 31.

End section 8 at the discharge end of the separator has an opening 43 centrally thereof which has an outwardly extending frusto-conical portion 44 attached thereto. About 35 the frusto-conical portion 44 is a filtrate collector 45. Filtrate collector 45 is more or less circular in form with an outlet 46 at the bottom thereof which discharges into a receiving pipe 47.

40 Filtrate collector 45 is so formed that a minimum amount of leakage occurs between it and the discharge end of the separator proper. Filtrate collector 45 has an inner wall 48 and an outer wall 49. The inner wall 48 over the upper half of the filtrate collector 45, as clearly shown in Figs. 3 and 6, is formed more or less U-shaped adjacent the outer edge of the frusto-conical portion 44 as clearly shown at 50. The purpose of this more or less U-shaped section is to catch liquid thrown upward at the outer edge of portion 44 by centrifugal force, returning same to the lower half of filtrate collector 45. Outer wall 49 also has an inwardly turned substantially U-shaped section 51, as clearly shown in Fig. 3, same extending within the outer edge of frusto-conical portion 44 and is for the purpose of catching liquid dropping from the upper half of the frusto-conical portion 44 and other liquid falling downward along the inner upper half of wall 45. The substantially U-shaped portion 51 extends over the upper half of filtrate collector 45, as shown in Fig. 6. An effective seal is

thus formed between filtrate collector 45 and frusto-conical portion 44.

The operation of the device is as follows: The liquid to be separated enters chamber 32 through inlet 40 and channel 29. A revolving motion is transmitted to the liquid and the heavier solid particles therein are thrown outward by centrifugal force and deposited around the outside of chamber 32. The larger particles readily separate from the liquid in this chamber. The sediment or foreign matter thus separated is caught by the cup 37 of channel 35 and flows out therethrough. The amount of liquid carried out with the sediment is controlled by valve 39. In other words, the valve 39 controls the fluidity of the sediment thus extracted. A very large percentage of the sediment and particularly the heavier particles are extracted in this manner, the percentage thereof depending upon the ratio of larger to finely divided particles of foreign matter contained in the liquid. As chamber 32 fills, the liquid flows into the separator body through the space between the inner circumferential edge of the frusto-conical portion 24 and collar 26 of the adjacent spider 9. Inside the separator body the liquid is forced to the periphery of the separator due to the fact that the adjacent spider 9 is closed for a portion thereof about the longitudinal axis of the separator.

It is to be noted that the liquid entering the separator body from the chamber 32 has foreign matter therein, a very large percentage of which is finely divided and too fine to be separated in the chamber 32. Upon being taken to the periphery of the separated body, the centrifugal force is greatly increased and the tendency of the finely divided particles to separate from the liquid is multiplied 100 many times. It will be noted that all of the spiders are shown closed about the longitudinal axis of the filter, causing all of the liquid to flow therethrough along the periphery. However, in liquid wherein the finely divided particles are not so difficult to separate, the last spider may have apertures 60, shown dotted, placed adjacent the longitudinal axis of the separator. This will speed 110 up action somewhat, or in other words, increase the capacity of the separator. In liquid containing a very high percentage of coarse particles, apertures 61, shown dotted, may also be placed in the second spider and adjacent the longitudinal axis of the separator.

115 It will be noted, however, that the first spider 9 forces all liquid to the periphery of the separator. The plates 15 are added in order to assist in revolving liquid at the same speed as the separator body. The finely divided particles of foreign matter separated with in the separator body, collect on the circumferential wall of the separator.

120 The filtrate is drawn off through opening 43, through frusto-conical portion 44 and fil- 130

trate collector 45. Inasmuch as a large portion of the sediment and other foreign matter is drawn off through passage 35, the amount of sediment deposited on the circumferential walls of the separator body is greatly reduced and the device may operate over a very much longer period of time. The percentage of sediment deposited in the separator body, however, is dependent upon the 10 percentage of finely divided particles, as is apparent to persons skilled in the art.

Cleaning of the separator body is accomplished through manholes 16, 17, 20 and 21. The sediment may be shoveled out by workers 15 entering the separator through the manhole, or same may be extrated by mechanical means from the outside of the separator.

Having thus described our invention, it is obvious that various immaterial modifications may be made in the same without departing from the spirit of our invention; hence we do not wish to be understood as limiting ourselves to the exact form, construction, arrangement and combination of 25 parts herein shown and described, or uses mentioned.

What we claim as new and desire to secure by Letters Patent is:

1. In a separator of the kind described, a 30 separator body, and variable means adjacent the inlet to said body for continuously extracting foreign matter from the liquid to be filtered before it enters said separator body.

35 2. In a device of the kind described, a separator body, a chamber adjacent the inlet to said body and separated from said body, means within said chamber including a stationary element for continuously separating foreign matter from the liquid, and means for 40 removing said foreign matter from said chamber while the device is in operation.

3. In a device of the kind described, a 45 separator body, a chamber adjacent the inlet to said filter body and separated from said body, means within said chamber for imparting a whirling movement to the liquid, and means for removing foreign matter from said chamber at will.

50 4. In a device of the kind described, a separator body, a chamber adjacent the inlet to said filter body and separated from said body, means for continuously feeding liquid to said chamber, and stationary means within said chamber distinct from said body, providing an element of means for continuously removing foreign matter from said liquid.

55 5. In a device of the kind described, a separator body, a protruding outlet for said body, a filtrate collector adjacent said outlet, said collector including means located upon opposite sides of the protruding outlet and providing means for retaining liquid thrown outward by centrifugal force.

60 6. In a device of the kind described, a sep-

arator body, an outlet for said body, a filtrate collector adjacent said outlet, said filtrate collector having means for collecting filtrate thrown from said outlet, an element of said collector being located within the outlet.

70 7. In a device of the kind described, a shaft, a plurality of spiders mounted upon said shaft, said spiders at the rims thereof formed T-shape, a sectional separator body, said sections of said separator body having flanges, said flanges attached to said spiders at the leg and bar of the T.

75 8. In a device of the kind described, a shaft, a plurality of spiders attached to said shaft, said spiders having enlarged circular rims, a sectional separator body, said sections of said separator body attached to said spiders within and engaging said enlarged circular rims.

80 9. In a device of the kind described, a shaft, a plurality of spiders attached to said shaft, said spiders having rims enlarged transversely thereof, a separator body comprising sections, said sections attached to said spiders and restrained centrally by said enlarged rims, and means for reinforcing said rims.

85 10. In a device of the kind described, a separator body, said body comprising a cylindrical casing of relatively large diameter, a primary separator chamber at the inlet to said body, means within said chamber to impart a whirling motion to the liquid, and means adjacent said chamber for continuously removing foreign matter separated from said liquid, an outlet for said separator body, and means about said outlet for collecting the filtrate.

90 11. In a separator and in combination, means for initially removing the larger particles of foreign matter from the incoming liquid and means for removing finely divided particles of foreign matter from said liquid, said last-mentioned means comprising a separator body and means opposite the mouth of said body for forcing the incoming liquid toward the periphery thereof.

95 12. In a centrifugal separator of the kind described, a hollow body, an inlet and outlet therefor positioned at opposite ends of said body and adjacent the longitudinal axis thereof, and means within said body for causing liquid flowing through said body to pass along the periphery thereof, said means comprising obstacles in the path of said liquid and positioned about the longitudinal axis of 100 said filter.

105 13. In a device of the kind described, means for initially and continuously removing relatively large particles of foreign matter from liquid, said means comprising a chamber, an impeller in said chamber and an outlet at the periphery of said chamber, and means for removing finely divided particles from said liquid, said means comprising a hollow body 110 connected to the outlet of said chamber, and

means within said body for causing liquid to flow therethrough along the periphery thereof.

14. In a centrifugal separator of the kind described, a hollow body, an inlet and an outlet therefor positioned at opposite ends of said body and adjacent the longitudinal axis thereof, and means within said body for causing liquid flowing through said body to pass along the periphery thereof, said means comprising obstacles in the path of said liquid and positioned about the longitudinal axis of said separator, at least one of said obstacles having an aperture for the passage of fluid adjacent said axis.

In testimony whereof, we have hereunto signed our names.

THOMAS RAY.
JOSHUA R. RAY.
